UNITED STATES PATENT OFFICE.

FRANK A. SHARPNECK, OF CHICAGO, ILLINOIS, ASSIGNOR OF NINETY ONE-HUNDREDTHS
TO REINHOLD REICHARDT AND LEE O. GILLILAND, OF CHICAGO, ILLINOIS.

ENGINE.

No. 887,855.

Specification of Letters Patent.

Patented May 19, 1908.

Application filed April 22, 1907. Serial No. 369,421.

To all whom it may concern:

Be it known that I, FRANK A. SHARPNECK, a citizen of the United States, residing at Chicago, in the county of Cook and State of Illinois, have invented certain new and useful Improvements in Engines, of which the following is a specification.

My invention relates to improvements in engines, and more particularly to engines of the rotating-cylinder, reciprocating-piston type, wherein the pistons reciprocate within cylinders mounted for bodily revolution about a stationary crank shaft.

One of the salient objects of my invention is to provide an engine of the character described, which is simple in construction and efficient in operation.

A further object of my invention is to provide an improved arrangement of cylinders and pistons whereby a compound effect may be secured to each cylinder.

Another object of my invention is to provide an improved valve gearing for such an engine, and other and further objects of my invention will become apparent to those skilled in the art from the following description taken in conjunction with the accompanying drawing, wherein;

Figure 1 is a side elevation with parts in section, of an engine embodying my invention; Fig. 2 is an enlarged view of a valve, indicated in Fig. 1; Fig. 3 is a side elevation thereof; Figs. 4 and 5 are enlarged details of an eccentric movement and a fluid pressure connection, suitable for employment in the engine.

Throughout the figures like numerals of reference refer always to like parts.

In the drawing 10—10 indicate frames, 40 supporting, and holding against rotation, the crank shaft 11, provided with two cranks 12, 12' which may conveniently align. One end of the crank shaft 11 is preferably hollow, as indicated at 13 in Fig. 5, and is connected to 45 the source of steam supply 14, an opening from the hollow portion of the shaft being afforded at 15.

Upon the crank shaft 11, are mounted for rotation the cylinder structure, comprising 50 preferably two pairs of cylinders, whereof the cylinders of each pair are arranged in alinement, and the pairs of cylinders as a whole are arranged at quartering relation or at right angles to each other. The cylinders

constituting each pair are identical in construction and I will, therefore, describe only one pair, whereof, 16 indicates one cylinder and 16' the other.

The cylinders and pistons are constructed to afford differential areas for the application 60 of the working fluid pressure upon opposite sides of the piston, and to this end the outer extremity of each cylinder is of relatively great diameter, as indicated at 17, and toward the axis of rotation is reduced in diameter, as at 18, the connecting shoulder 19 forming the head of the high pressure side of the cylinder, and a suitable head 20 being provided in the low-pressure side of the cylinder. Cylinder 16' is similarly constructed, its parts 70 being indicated by like numerals of reference differentiated by the exponent prime (').

The pistons of the two cylinders, which may be integrally connected, provide heads 22, 22', interfitting in the cylinder portion 17, 75 17', integrally connected hollow trunks 23, 23' interfitting in the reduced portions 18, 18', such connected trunks being provided with slots 24, receiving the crank shaft 11. The opposite, connected pistons may be connected with the crank 12 by means of a single 80 piston rod 25, suitably pivoted to one of the piston heads, as 22'.

Steam is supplied to the various cylinders from a rotating main fitting 27, upon the shaft 85 11, said fitting having therein a chamber 28, constantly communicating through orifice 15 in the shaft, with the primary source of steam supply, and said fitting being provided with four radiating supply pipes 29, one for 90 each cylinder, each such supply pipe having therein a valve fitting 30, controlling all the steam connections of the cylinder. To this end there are provided in connection with said fitting an exhaust pipe 31, a high pressure pipe 32 communicating with the clearance on the high pressure side of the piston, and a low pressure connection 33 communicating with the clearance on the low pressure side of the piston. Within the fitting 20 is 100 arranged an oscillating valve 34, provided with a cutoff extension 35, and arranged for actuation through movement of the lever 36, the parts being so arranged in movement of valve lever 36 to one end of its throw cuts off 105 pipe 27 and opens pipes 32 and 33 to inter-communication, as shown in full lines in Fig. 5, while movement of the valve at the other

end of its throw, as indicated in dotted lines in Fig. 5, opens communication between pipes 27 and 32 and between pipes 31 and 33.

For automatically actuating all of the valves in proper timed relation, I provide upon the stationary shaft 11 a stationary eccentric 37, surrounded by an eccentric strap 38, arranged to be carried in rotation by the revolution of the cylinder body. Effective 10 connection may be established between the handles 36 of the several controlling valves and the eccentric ring, or strap 38, through bell-crank levers 39 mounted on brackets 40 provided on the piping connections 29, and links 41, 42 respectively connecting said bell-crank lever with the arm 36, and the ring 38. To provide for rotation of the eccentric ring 38, the connection of one link 42 thereto, may be made comparatively rigid, while to 20 permit necessary flexibility between the valve mechanism and the eccentric rings, the remaining links 42 may be connected to the ring by ball and socket joints, as indicated in Fig. 4.

25 The operation of the device above described will be as follows: When the pistons are in the position shown to the left in Fig. 1, the controlling valves associated with cylinder structure 16, stand in the position to afford communication between the supply pipe 29 and the high pressure pipe 32, and between the low pressure pipe 33 and the exhaust pipe 31. Under such conditions steam flows into the high pressure end of the 30 chamber 17, to act upon the relatively small annular surface exposed to such end of the piston head 32. At the same time in the opposite cylinder 16' connection between the high pressure and low pressure pipes 32 and 33 is opened and the supply pipe 29 is cut off, so that previously introduced high pressure steam may flow to the low pressure side of the piston, to act, in conjunction with the steam introduced into the high pressure side 35 of the cylinder 16, to force the pistons to the opposite ends of their respective cylinders, the connection between the connected pistons and the crank arm 12 effecting a resultant half rotation of the cylinders with respect to the crank. During such movement 40 the position of the ring 38 with respect to its eccentric is reversed, so that through the link and lever connection the positions of the valves are reversed, and the cylinder 16' is operated on its high pressure side, while in 45 the cylinder 16 the high pressure steam is transferred to low pressure side and acts to assist in the next half rotation, the arrangement of the transfer connection and exhaust 50 pipe, it will be observed, facilitates drainage and prevents accumulation of the water of condensation. It will be apparent, therefore, that during each revolution the cylinder structure received the four distinct impulses 55 from the several cylinders, and that each im-

pulse coördinates the effect of the high pressure action of one cylinder and the low pressure action of the opposing cylinder. Further it will be seen that in starting it is not necessary to vary the valve arrangement and 70 employ a low pressure cylinder with high pressure steam.

While I have herein described one embodiment of my invention for purposes of disclosure, it will be understood that various 75 changes in the construction may be made without departure from the spirit and scope of my invention.

Having thus described my invention, what I claim and desire to secure by Letters 80 Patent, of the United States, is:

1. An engine comprising a stationary crank shaft, balanced cylinders revoluble about said crank, pistons in said cylinders, each exposing to the fluid action differential 85 areas on opposite sides thereof, mechanical connections between the pistons and the crank shaft, steam connections between the high and low pressure ends of the cylinders, fluid supply and exhaust connections, and 90 means for controlling the connections.

2. An engine comprising a stationary crank, balanced cylinders revoluble about said crank, connected pistons in said cylinder, each exposing differential areas to the 95 fluid action on opposite ends thereof, mechanical connections between the pistons and the crank, fluid supply connections to the high pressure side of each piston, transfer connections between opposite sides of each 100 piston, exhaust connections for the low pressure side of each piston, and means controlling said connections to open the steam supply to the high pressure side of the piston and open the exhaust connections, and close the 105 transfer connections of one cylinder, while in the other cylinder the steam supply and exhaust connections are inoperative and the transfer connections opened.

3. An engine comprising a crank, opposing 110 cylinders, said crank and cylinders being revoluble one with respect to the other, each cylinder providing a portion of large diameter and a portion of smaller diameter, pistons in said cylinders each having a head in the portion of larger diameter, and having hollow trunks in the portions of smaller diameter, connections between said crank and said pistons, means of fluid pressure supply to the side of the piston affording the smaller 115 area, means of exhaust from the side of the piston of larger area, and means for effecting connection between the opposite sides of said piston.

4. An engine comprising a stationary 125 shaft, a rotatable cylinder structure, comprising a cylinder having opposite heads of different areas, a piston presenting corresponding areas therein, a steam supply connection for the high pressure side of the 130

cylinder, an exhaust connection for the low pressure side of the piston, a transfer connection between said sides of the piston and a single valve for said connections arranged to 5 close the steam supply connection when opening the transfer connection, and to open the steam supply and exhaust connections when closing the transfer connection.

5. An engine comprising a crank shaft, 10 and a cylinder structure, one rotatable relative to the other, said cylinder structure having a cylinder therein providing high and low pressure ends of different areas; a piston in said cylinder exposing to fluid action differential areas on opposite sides thereof; 15 mechanical connections between the piston and crank shaft; fluid connections between the high and low pressure ends of the cylinder, fluid supply and exhaust connections 20 for said cylinder, and means controlling the connections.

6. An engine comprising a shaft, and a cylinder structure, one rotatable relative to the other, said cylinder structure comprising a cylinder having opposite heads of different 25 areas; a piston presenting corresponding areas on opposite sides arranged therein, a fluid supply connection for the side of lesser area of the piston; an exhaust connection for the side of greater area of the piston; a 30 transfer connection between said sides of the piston, a single valve for said connections arranged to close the supply and exhaust connections when opening the transfer connection, and vice versa, and means for operating said valve.

In testimony whereof I hereunto set my hand in the presence of two witnesses.

FRANK A. SHARPNECK.
